LEG FOR A TABLE OR SIMILAR ARTICLE

Albert W. Lindberg, Jr., 125 W. 6th St., Bayonne, N.J.

Filed Oct. 15, 1957, Ser. No. 48,107

Term of patent 3½ years

(Cl. D33—14)

Fig. 1 is a perspective view of a leg for a table or similar article embodying my new design.

Fig. 2 is a section taken on line 2—2 of Fig. 1.

The two faces of the leg not shown are substantially the same as the faces shown.

I claim:

The ornamental design for a leg for a table or similar article, as shown and described.
